TELEPHONE SYSTEM

Johannes Boysen, Berlin, Germany, assignor to
Siemens & Halske Aktiengesellschaft, Sie-
mensstadt, near Berlin, GermanyApplication December 9, 1932, Serial No. 646,422
In Germany January 27, 1932

10 Claims. (Cl. 173—16)

The present invention relates to a circuit arrangement for carrying out switching operations by means of relays caused to operate over neon lamps and used more particularly in telephone systems. This type of arrangement, however, is defective in that in addition to the existing exchange battery other current supplies have to be provided, such as, for example, alternating current generators, transformers, additional battery, etc., due to the fact that as a rule the striking voltage is considerably higher than the battery voltages generally used in such systems.

According to the present invention, however, such additional current supplies are unnecessary due to the feature that the additional potential required to raise the normal battery voltage to the striking voltage for a neon lamp can be generated by charging a condenser by means of the ordinary exchange battery potential which is lower than the striking voltage.

The accompanying drawing illustrates an embodiment of the invention applicable to the telephone art. The diagram represents an automatic telephone system employing two-wire junction lines. The invention is used with advantage in such systems for the release of connecting devices disposed at the incoming end of a two-wire junction line. Only the switching operations of any importance for the nature of the invention will be described below.

When the junction line VL is seized at its incoming end, for example, by a preceding first group selector, relay C is connected to battery over the c-lead and therefore energized. This relay transmits the seizing operation in any known manner to the second group selector located at the incoming end. The associated switching operations have not been shown. Contacts 2c and 4c are closed on the energization of relay C. One side of the condenser K is then connected to the positive pole of the exchange battery and the other side to the negative pole and the condenser K in question is charged up to the voltage of this battery which in the present example has a value of 60 volts. The closing of contact 1c completes a circuit for relay F which closes its contact f but this has no effect due to contact 3c having been opened previously.

The further switching operations associated with a completion of the connection such as the transmission of impulse series, etc., are now carried out. These operations, however, have no bearing on the present invention and therefore are not described.

At the end of the call the release takes effect

from the outgoing end of the junction line whereupon the c-lead from the preceding first group selector is cut off. Relay C then restores, opens its contact 1c and thereby breaks the circuit for relay F. The release of relay F is greatly retarded, with the result that contact f remains closed a certain period after the release of relay C. The opening of contacts 2c and 4c and the closing of 3c and 5c throws the lead for the condenser K (now charged with 60 volts) which was previously connected to the positive pole of the battery over to the negative pole of the battery with the result that the other condenser lead carries a potential double that of the exchange battery, i. e., 120 volts. This potential which, due to the slow release on the part of relay F is applied for a certain period to the b-lead of the junction line VL is sufficiently high to cause the neon lamp GL in the second group selector at the incoming end of the junction line VL to be lighted. The operation is carried out over the following circuit: earth, battery, contact 5c, condenser K, contacts 3c, f, b-lead of the junction line VL, neon lamp GL, winding of relay R, to earth. The condenser is discharged on the lighting of the neon lamp and in this discharge circuit relay R associated with the second group selector operates and opens its contact r which cuts off the test circuit to the succeeding switch and initiates its release. The test relay P in the second group selector relapses and initiates the release of this switch in known manner.

At the outgoing end of the junction line the condenser K is disconnected from the b-lead of the junction line VL on the opening of contact f so that the system is now restored to normal.

What is claimed is:

1. The combination with a neon tube, of a battery whose potential is below the striking voltage of the tube, a condenser charged to the potential of said battery, and means for connecting said condenser and said battery in series so that the discharge from the condenser aids the battery to transmit an impulse of current at a potential above the striking voltage of the tube to said tube.

2. The combination comprising a neon tube, a battery whose potential is below the striking voltage of said tube, a condenser, means for connecting the two plates of the condenser to the two terminals of the battery, and means for reversing the connection of one plate of the condenser with respect to the battery terminals and for connecting the other plate of the condenser to the tube to operate the same.

3. In combination, a conductor, a neon tube

connected to said conductor and ground, a condenser, a source of current of a potential below the striking voltage of the tube, means for connecting the plates of said condenser to said current source and ground, respectively, and means for switching one condenser plate from ground to said current source and for switching the other condenser plate from said current source to said conductor to operate the tube.

10. 4. In combination, a neon tube, a battery whose potential is below the striking voltage of said tube, a condenser, a relay, contacts closed by said relay for connecting said condenser across said battery, and other contacts closed by said relay for connecting said battery, said condenser, and said tube in series to operate the tube.

5. In combination, a neon tube, a battery whose potential is below the striking voltage of said tube, a condenser, two relays, contacts closed by 20 the first relay for connecting said condenser across said battery, and other contacts closed by said relay for connecting said battery, said condensers, said tube and said second relay in series to strike the tube and operate the second relay.

25. 6. In a telephone system, a trunk, a neon tube connected to a conductor of the trunk, a battery whose potential is below the striking voltage of the tube, a condenser, means for seizing the trunk, means responsive to the seizure of the trunk for connecting said condenser to said battery to charge the condenser, and means responsive to the release of the trunk for connecting said condenser to one trunk conductor to operate said tube.

7. A telephone system, as claimed in claim 6, in which the trunk includes a test lead and in which the means for connecting the condenser to the battery and to the test lead comprise contacts controlled by a relay operated over the test lead. 5

8. A telephone system, as claimed in claim 6, in which the neon tube is connected to the trunk conductor in series with a relay which is adapted to control the release of a connection extended over the trunk. 10

9. In a telephone system, a trunk including talking conductors, a test conductor at each end of the trunk, a relay connected to the test conductor at the outgoing end of the trunk, a neon tube and a relay connected to a talking conductor at the incoming end of the trunk, a battery whose potential is below the striking voltage of said tube, a condenser, contacts controlled by said first relay for connecting said conductors to said battery to charge the condenser, other contacts controlled by said first relay for connecting said condenser and said battery to said one talking conductor to operate the tube and said second relay, and contacts controlled by said second relay for opening the test conductor at the incoming 20 25 end of the trunk.

10. A telephone system, as claimed in claim 9, in which a slow releasing relay controlled by the first relay controls contacts for disconnecting the condenser and battery from the talking conductors of the trunk. 30
